UNITED STATES PATENT OFFICE.

FREDERICK F. BIOREN AND JAMES C. BIOREN, OF NEWARK, NEW JERSEY.

DESIGN FOR A SLEEVE-BUTTON.

SPECIFICATION forming part of Design No. 15,003, dated May 20, 1884.

Application filed February 16, 1884. Term of patent 7 years.

To all whom it may concern:

Be it known that we, FREDERICK F. BIOREN and JAMES C. BIOREN, citizens of the United States, residing at Newark, in the county of Essex and State of New Jersey, have invented a certain new and original Design for Sleeve-Buttons and other Articles of Jewelry; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan of a sleeve-button or other piece of jewelry embodying our design, and Fig. 2 is a side elevation of the same, said figures being deemed sufficient to illustrate the nature of the design, which consists in the sleeve-button or other similar article of jewelry having the shape hereinafter described.

The said drawings represent a piece of jewelry, *a*, with a letter-shaped protuberance, *b*, the comparatively regular outline surfaces *c c* of which lie at an angle or project from the surface *d* of said piece of jewelry, as shown. The letter-shaped projecting portions may

have the configuration of any of the letters of the alphabet. Between the surfaces *c c* the raised surface or surfaces are filled in with flower-shaped projections, or are shaped in imitation of a collection or mixture of flowers, as distinguished from a mixture of flowers and leaves, as shown in a contemporaneous application filed by us on the 3d day of November, A. D. 1883, and having the serial number 110,823.

The flowers may be formed in imitation of natural ones; or they may be conventionalized, and the shape and relations of the individual flowers may be changed to suit each and any of the various letter shapes that may be made.

What we claim is—

In a sleeve-button or other similar article of jewelry, the design which consists in the initial letter, as shown and described.

In testimony that we claim the foregoing we have hereunto set our hands, this 11th day of February, 1884.

FREDERICK F. BIOREN.
JAMES C. BIOREN.

Witnesses:

CHARLES H. PELL,
F. F. CAMPBELL.
